UNITED STATES PATENT OFFICE.

CHARLES HIGGINS AND JOHN GREGORY, OF CLAY CITY, ILLINOIS.

TRACTION-ENGINE.

SPECIFICATION forming part of Letters Patent No. 460,375, dated September 29, 1891.

Application filed May 25, 1891. Serial No. 394,004. (No model.)

To all whom it may concern:

Be it known that we, CHARLES HIGGINS and JOHN GREGORY, citizens of the United States, and residents of Clay City, in the county of 5 Clay and State of Illinois, have invented certain new and useful Improvements in Traction-Engines; and we do hereby declare that the following is a full, clear, and exact description of the invention, which will enable 10 others skilled in the art to which it appertains to make and use the same, reference being had to the accompanying drawings, which form a part of this specification.

Our invention relates to improvements in 15 traction-engines of that class known as "top-mounted center-crank engines," in which the axle carrying the traction-wheels is driven by means of belts and pulley-wheels actuated by a crank-shaft which receives its motion 20 from the engine-cylinder.

One of the objects of the invention is to 25 provide an improved construction and arrangement of devices for tightening the driving-belts. It is also an object to provide a housing or casing for the belts and pulleys, whereby they are protected from mud and dirt.

The invention consists in the novel construction and combination of parts hereinafter 30 fully described, and specifically pointed out in the claim.

In the accompanying drawings, Figure 1 is 35 a side view of a traction-engine constructed according to our invention, the side or outer wall of the casing or housing being removed. Fig. 2 is a plan view of the engine.

In the said drawings, the reference-numeral 1 designates an ordinary steam-boiler suitable for this class of engines, supported at 40 the front by axle 2 and wheels 3 and at the rear by axle 4 and traction-wheels 5. The latter may be provided with the ordinary pins or projections. Mounted upon the top, the boiler in rear of the smoke-stack, is the cylinder 45 7, the piston-rod 8 of which is connected with the crank-shaft 9, journaled in bearings secured to the boiler and carrying at its outer ends flanged pulleys 10. The rear or driving axle also carries two pulley-wheels 12, 50 which are keyed or otherwise secured to the hubs of the traction-wheels, and over these pulley-wheels and the pulleys 10 pass loose endless belts 13. Projecting outwardly from the boiler at each side are two short shafts

14, which are rigidly secured to the boiler 55 and upon which are pivoted the upwardly-extending arms 15, connected together at their upper ends by pivot rods or shafts 16, which are journaled therein and which carry the flanged belt-tightener wheels 17. Connected with the inner arm 15 at each side of the boiler is a crank-arm 18, connected by means of rods 19 with lever 20, pivoted to the boiler near the rear end thereof. These levers work in slotted segments 21, secured 65 to the boiler and provided with ratchet-teeth 22, which engage with said levers and hold them in position.

The numeral 23 designates a casing or housing of sheet metal or other material secured 70 to the boiler and entirely surrounding the pulley-wheels, pulleys, and belts connecting the same, so as to protect them from mud and dirt.

The operation will be readily understood. 75 The belts are tightened by pulling the levers 20 backward, which, through the medium of the rods 19, will force the tightener-wheels against the belts and thus cause them to be brought into frictional contact with the pulley-wheels and pulleys. A reverse movement will loosen the belts, as will be obvious. The belt-tighteners and pulley-wheels being 80 on each side of the engine and being entirely separate and distinct, those on either side can 85 be removed and replaced independently of each other.

Having thus described our invention, what we claim is—

In a traction-engine, the combination, with 90 the boiler, the cylinder, the crank-shaft carrying driving-pulleys, the traction-wheels and axle, the pulley-wheels secured to said traction-wheels, the loose belts connecting said pulley-wheels and pulleys, and the belt-tighteners, of the housing or casing secured to the boiler and surrounding and inclosing the pulley-wheels, pulleys, belts, and belt-tighteners, substantially as described.

In testimony that we claim the foregoing as 100 our own we have hereunto affixed our signatures in presence of two witnesses.

CHARLES HIGGINS.
JOHN GREGORY.
